TOY GOLF CLUB

Thomas G. Bergstrom, 1321 Appeal Ave., Elmont, N.Y.

Filed Oct. 22, 1964, Ser. No. 82,282

Term of patent 14 years

(Cl. D34—5)

FIG. 1 is a perspective view of the front and side of a toy golf club showing my new design,
FIG. 2 is a top view,
FIG. 3 is a side view, and
FIG. 4 is a rear view.

The essential features of my design reside in the portions shown in full lines.

I claim:
The ornamental design for a toy golf club, substantially as shown and described.
